UNITED STATES PATENT OFFICE.

LOUIS S. KURTZMANN, OF BUFFALO, NEW YORK, ASSIGNOR, BY MESNE ASSIGNMENTS,
TO KURTZMANN PHONOGRAPH COMPANY, INC., OF BUFFALO, NEW YORK.

PHONOGRAPH OR THE LIKE.

Application filed October 30, 1918. Serial No. 260,340.

To all whom it may concern:

Be it known that I, LOUIS S. KURTZMANN, a citizen of the United States, residing at Buffalo, in the county of Erie and State of New York, have invented a new and useful Improvement in Phonographs or the like, of which the following is a specification.

This invention relates to phonographs, gramophones or analogous devices of the kind in which sound is produced by means of a needle or stylus and reproducing mechanism, co-operating with a groove on a record.

It is well known that the material used in the construction of musical instruments has an important bearing upon the sounds produced and in the construction of phonographs a great improvement has been found in the quality of the tone produced, when the supporting base of the instrument and the turn-table or other support for the record are made of certain materials. I have found that the use of glass in a phonograph, for example the use of a glass base on which the driving and controlling mechanism is mounted, or a glass turn-table or support for the record, not only produces a clearer and better reproduction of the record, but also greatly reduces the surface noise or scratching sounds usually produced in instruments of this kind.

The objects of this invention are to produce a phonograph of this kind in which certain parts of the instrument are made of glass or the like to effect a better reproduction of the sound.

In the accompanying drawings:

Fig. 1 is a front elevation of a phonograph or analogous device embodying the invention.

Fig. 2 is a top plan view thereof.

Fig. 3 is a fragmentary central sectional elevation thereof.

The case or housing of the phonograph may be of any desired shape, that shown in the drawings have four legs A, on the upper portions of which the parts of the phonograph are arranged.

A base plate B is arranged at the upper portions of the legs and the parts of the phonograph are mounted on this base plate. It has been found that the best results can be obtained if this plate is made of glass. The plate may be secured to the frame in any suitable manner, for example a flanged

metal frame b is provided in the construction shown, which is secured to the upper ends of the legs A by suitable means, such as screws b', and the edges of the frame extend upwardly around the sides of the base plate B and hold the base in place. The plate B preferably rests on disks or cushions b² of felt or other yielding material.

C represents the turn-table or support for the record. This turn-table is preferably also made of glass and the record is placed on the upper face thereof, a pin c of the usual kind extending through the usual central hole in the record for centering the same on the turn-table. The turn-table may be rotatably mounted on the glass base B in any suitable manner. In the construction shown the glass plate C forming the turn-table is suitably secured to a disk c' by any suitable means, such as screws c² extending through holes in the glass turn-table C. The disk c' is provided with the usual post or bearing stud c³ which is suitably journaled in a plate c⁴ which is secured to the glass base B by any suitable means, such, for example, as screws or bolts c⁵ extending through holes in the glass base. Suitable pads c⁶ and c⁷ are preferably inserted between the disk c' and the glass turn-table C and between the plate c⁴ and the base B.

The mechanism for rotating the turn-table may be of any suitable or desired construction, and is preferably mounted on the glass base B. In the construction shown, the turn-table is rotated by means of an electric motor D suitably mounted on the plate c⁴ secured to the lower face of the base and connected by any desirable driving means (not shown) with the pin or stud c³ of the turn-table. The operation of the motor is controlled by means of a switch d which is preferably mounted on the upper face of the base B. The speed at which the turn-table is rotated is preferably controlled by means of the usual speed controlling means E which are also mounted on the glass base B. The motor D, the controlling switch d, and the speed controlling means E have heretofore been used on phonographs and of themselves constitute no part of this invention.

The sound is reproduced from the record by means of the usual reproducer F mounted on a tone arm f which is secured to the

glass base B in any suitable manner, for example by means of screws or bolts f' extending through holes in the glass base. The end of the tone arm connects with the usual 5 horn G arranged below the base and suitably supported from a sounding board or the like H by means of a post h.

The horn and driving mechanism may be enclosed by suitable side walls I, which 10 may be of any desired material, glass being employed in the construction shown.

I have found that by using a glass base as described, and by using a glass turn-table C, the sounds produced by the instrument differ greatly in quality from those 15 produced in instruments in which the base B and the turn-table C is made of wood, metal or other materials heretofore used. The instrument constructed as described produces a greater volume of tone 20 and also a clearer tone than other instruments heretofore made and has the property of very materially reducing the surface noises or scratching sounds produced 25 by the needle as the same passes over the record, so that a more nearly perfect reproduction of the sounds is effected than has heretofore been possible. The noises

due to the operation of the mechanism for driving the turn-table, are also very mate- 30 rially reduced by means of the glass base.

It will be understood that it is not intended to limit the invention to the form or construction of the housing or case of the phonograph nor to the reproducing or operating devices, since the glass base and the glass turn-table may be used in phonographs or analogous devices of any other desired construction or shape, and in connection 35 with other reproducing or operating de- 40 vices.

I claim as my invention:

In a phonograph or the like, the combination of a rotatable record supporting member, driving mechanism for rotating said record supporting member, a sound reproducing device, and a glass base on which 45 said supporting member, said driving mechanism and said reproducing device are mounted.

Witness my hand, this 29th day of October, 1918.

LOUIS S. KURTZMANN.
